HOLDER FOR CIGARS AND CIGARETTES

Joseph Daugherty Kilgore, Athens, Ohio, assignor of one-half to Edward Alvin Cottingham, Athens, Ohio

Application March 16, 1943, Serial No. 479,325

1 Claim. (Cl. 131—190)

This invention relates to cigarette and cigar holders or more particularly to a holder which may be used for either cigarettes or cigars.

An object of this invention is to provide a holder which will securely hold a cigarette or a cigar without crushing it.

A further object is to provide a holder in which the butt of the cigarette may be easily disposed of. A still further object is to provide a holder with an adjustable chuck and a proper filter.

In the accompanying drawing,

Figure 1 shows a cross sectional view of my improved holder with the chuck retracted.

Figure 2 is a cross sectional view with the chuck extended.

Figure 3 is a cross sectional view taken on the line 3—3 of Figure 1.

Referring more particularly to the drawing, my holder 10 consists of a casing 11 and a bit 12. The bit 12 has a bore 13 to allow the passage of smoke and its forward end is bored out to form a filter chamber 14 in which filter 15 may be positioned. The filter 15 may consist of any filter or a part of a cigarette or plug of tobacco. The front of the bore 13 is internally threaded at 16 to hold the plug 17. The plug itself is bored and internally threaded at 18 to engage the connecting nipple 19.

The shell 11 is provided with an internal annular flange 20 against which the coil spring 21 may be positioned. The spring 21 not only abuts the annular flange 20 but also engages the

plug 17 and surrounds the threaded tube or nipple 19.

At the end of the nipple 19 is a chuck 25. This consists of a tapered soft rubber tube 26 reinforced by flat spring wires 27 which are bent inwardly to form a contact surface 28. The inner ends of the spring wires 27 covers the tube 26 and are fastened over a tapered nut 29 by means of the bushing 30 and the nut 31.

My holder may be easily disassembled by unscrewing the bit 12 whereby the spring 21 may be removed and the remaining portion pushed forwardly out of the shell 10.

In use the bit 12 may be pushed forwardly within the shell 10 to move the chuck 25 out of the end 32 of the shell. A cigarette or cigar may then be inserted within the chuck and the bit allowed to slide rearwardly until the article is firmly gripped. When a filter is used, it may be used over and over, and when a part of a cigarette is used as a filter, it may be replaced whenever needed.

I claim:

A cigarette holder or the like including a shell, a bit slidably mounted within said shell, and a chuck member secured to said bit and movable therewith, said chuck member comprising a tapered rubber tube supported by a plurality of flat spring members, and said spring members being bent inwardly about the outer edge of said tube to form a bearing surface.

JOSEPH DAUGHERTY KILGORE.
